US00D900281S

(12) **United States Design Patent** (10) **Patent No.:** **US D900,281 S**
Liu (45) **Date of Patent:** **** Oct. 27, 2020**

(54) **WALL MIXER**(71) Applicant: **Phoenix Industries Pty Ltd**,
Bayswater, Victoria (AU)(72) Inventor: **Ban Hsi Liu**, Bayswater (AU)(73) Assignee: **Phoenix Industries Pty Ltd**, Bayswater
(AU)(***) Term: **15 Years**(21) Appl. No.: **29/678,504**(22) Filed: **Jan. 29, 2019**(30) **Foreign Application Priority Data**

Jul. 30, 2018 (AU) 201814525

(51) **LOC (12) Cl.** ..... **23-01**(52) **U.S. Cl.**USPC ..... **D23/238**(58) **Field of Classification Search**

USPC D23/238-242, 254, 255
